(57) **CLAIM**

The ornamental design for a front cover of a 2U data storage subsystem, as shown and described.

DESCRIPTION

FIG. 1 is a perspective view of a front cover of a 2U data storage subsystem;

FIG. 2 is a perspective view illustrating where the front cover of a 2U data storage subsystem is located in a 19-inch equipment rack;

FIG. 3 is a front view thereof;

FIG. 4 is a top plan view thereof;

FIG. 5 is a bottom plan view thereof;

FIG. 6 is a side view of one end thereof; and,

FIG. 7 is a side view of the other end thereof.

The broken lines shown in the various Figures are shown for illustrative purposes only and form no part of the claimed design.
